UNITED STATES PATENT OFFICE

148,597

DESIGN FOR A COMBINED MANTEL CLOCK
AND PLANT RECEPTACLES

Norman H. Abrams, Indianapolis, Ind.

Application October 21, 1947, Serial No. 142,066

Term of patent 3½ years

(Cl. D42—7)

To all whom it may concern:

Be it known that I, Norman H. Abrams, a citizen of the United States, residing at Indianapolis, in the county of Marion and State of Indiana, have invented a new, original, and ornamental Design for a Combined Mantel Clock and Plant Receptacles, of which the following is a specification, reference being had to the accompanying drawing, forming part thereof.

In the drawings, Fig. 1 is a front perspective view of a combined mantel clock and plant receptacles, showing my new design. Fig. 2 is a top plan view thereof.

I claim:

The ornamental design for a combined mantel clock and plant receptacles, as shown.

NORMAN H. ABRAMS.
